Res. 2333

John H. Bellamy of Charlestown, Mass.

Letters Patent No. 2333. Dated June 12, 1866.

Design for a Bracket.

The schedule referred to in these Letters Patent and marking part of the same.

To whom it may concern.

Be it known, that I, John H. Bellamy of Charlestown, in the County of Middlesex and State of Massachusetts have invented or produced a new and original design for a Bracket, & hereby declare that the following is a full and exact description of the same, reference being had to the accompanying drawings and to the letters of reference numbered therewith:

The nature of my invention or production consists of a design for a bracket embracing certain emblematic symbols which constitute principally the body and outline of it, and which are arranged relatively in the construction of it, as follows to wit:

The bracket consists of back (1) in open work representing above the shell (3) an arch (1) with keystone (2) the arch (1) supported by cornithian columns (3) which comprise its outside above the (3) shell, at the top centre of which inside are the square (4) and compass (5) enclosing the latter a (6) and supported by two parallel lines (7) on the left enclosing a circle (8) and book (9) and by a

2

three round ladders (10) on the right, said parallel lines and ladders being joined by a 24 inch gauge (11) and gauge (12) resting upon a 6-hour glass (13) with wings (14) attached. Beneath the shelf (15) the bracket consists of a trumpet (15) forming the centre, on the left side of which is a scroll (16) enclosing a plumb (17) & on the right a scroll (18) enclosing a square (19) there being at the bottom centre a level (20) joined to the handle of said trumpet (15) the shelf (15) being supported by a square (21) and an ornamental letter G (22).

What I claim as my invention and production & desire to secure by letters patent is the design for a bracket as shown and described
